UNITED STATES PATENT OFFICE.

PHILLIPS P. BOURNE, OF WINCHESTER, MASSACHUSETTS, ASSIGNOR TO WORTHINGTON PUMP & MACHINERY CORPORATION, OF NEW YORK, N. Y., A CORPORATION OF VIRGINIA.

OIL-ENGINE-DRIVEN CENTRIFUGAL AND SIMILAR PUMP.

Application filed November 13, 1923. Serial No. 674,437.

This invention relates to the control of internal combustion engines and especially to an improved control for internal combustion engines driving centrifugal pumps or the like and is especially adapted for such use in installations drawing water from rivers or the like where there is or may be a considerable variation in the water level. This condition prevails to a great extent in irrigation installations where a decrease in the suction head results in the pump delivering a larger quantity of water with consequent overloading of the pump and increase of the fuel supply to the engine which may produce bad combustion and result in a breakdown or stoppage of the engine, and, in any case, involves increased cost of operation without any resulting advantage, as any excess of water delivered above what is necessary for irrigation is wasted. The most economical and efficient pump operation of an irrigating system is that which delivers a uniform quantity of water, irrespective of supply level, with the minimum fuel consumption.

It is an object of this invention to provide an improved control for the internal combustion engine of a centrifugal or similar non-displacement pump, which will maintain a uniform pump capacity at a minimum fuel-consumption, regardless of the variation in pump lift, and provide an adjustably fixed limit of the fuel to that amount which can be effectively and properly burned therein.

A further object is to provide a simple and efficient control of general application in internal combustion engines combining a speed responsive control of the fuel with a second adjustable control providing an adjustably fixed limit for the maximum amount of fuel to be delivered to the engine cylinders and operating to render the speed responsive control inoperative except for quantities of fuel less than the adjustably fixed maximum quantity.

For a full understanding of the invention a construction embodying all the features thereof in their preferred form will now be described in connection with the accompanying drawings forming a part of this specifi-

cation and the features forming the invention then specifically pointed out in the claims.

In the drawings—

Figure 1 is a side elevation of an internal combustion engine driven centrifugal pump unit;

Figure 2 is a section through the internal combustion engine control box,

Figure 3 is a section on line 3—3 of Fig. 2, Figure 4 is a section on line 4—4 of Fig. 2, and,

Figure 5 is a section on line 5—5 of Fig. 4.

Referring to the drawings, the centrifugal pump A may be directly connected to the internal combustion engine B by a suitable flexible coupling C to form a unit therewith and the operation of the internal combustion engine B is controlled by mechanism mounted within a control box D mounted at one end thereof, and on which is mounted the fuel pump body E with a plurality of fuel pumps, one for each cylinder of the engine.

As shown in Fig. 3, each fuel pump is provided with the usual pump plunger 7 and suction and discharge passages 1, 2, controlled respectively by suction valve 3 and discharge valve 4. The suction passage 1 connects with a fuel supply chamber 5, common to all the pumps, and the discharge passage 2 connects with one of the engine cylinders through the piping 6. The pump plunger 7 is actuated in any suitable manner, as by tappet 8 moved by engagement with the roller 9 of a strap eccentric 10 mounted on the engine crank shaft 11 which extends within the control box D. The pump has a variable delivery which is of the suction bypass type in which the suction valve 3 is held open during a varying time in the latter portion of the stroke of the plunger 7 by means of a by-pass plunger 12 moved by bypass tappet 13 at the proper time. The bypass tappet 13 is moved by the movement of plunger tappet 8 through a by-pass lever 14 pivoted at one end to the plunger tappet 8 and having its opposite end resting upon an eccentric fuel control shaft 15 adjustable under the control of a speed responsive device to determine the time and period of

opening of the suction valve 3 for by-passing the fuel.

This speed responsive device comprises a governor base 16 secured to the engine crank shaft 11 and mounting pivotally weights 17 which have arms bearing against the face of a sleeve 18, axially movable on the crank shaft 11 and provided with shrouds 19 between which the forked ends 20 of a bifurcated lever 21 extend. The bifurcated lever 21 is secured to and supported by a shaft 22 to which is also secured a governor arm 23 connecting with the lower end of an adjustable link 24 preferably by a sliding joint 15 formed by providing a passage through the governor arm 23 through which the adjustable link passes freely, a head 25 on the end of the link 24 coacting with the governor arm 23 for movement of the link 24 downward. The upper end of the adjustable link 24 is pivoted to one end of a lever 26, the opposite end of which is secured to the eccentric fuel control shaft 15.

The lever 26 preferably comprises a hub 25 secured to the eccentric fuel control shaft 15 by a pin 28 and provided with two parallel lever arms 29 connected at their outer ends by a pivot pin 30 rotatable therein to which is secured the forked end 31 of the adjustable link 24. A light spring 32 secured at one end to control box D and at the other to an eye 33 carried by a pin 30 holds the head 25 of the adjustable link 24 in engagement with the end of the governor arm 23.

For adjustably fixing the maximum fuel limit I provide the hub 27 with a peripheral recess 34 forming a shoulder 35 coacting with a pin 36 carried by a hand lever 37 loosely mounted upon the eccentric fuel control shaft 15, preferably between the hub 27 and the control box D. The hand lever 37 is provided with a handle 38 for movement thereof and with a bolt 39 which passes through an arcuately slotted plate 40 secured to the control box D by bolts 41, a suitable thumbscrew 42 being provided on the bolt 39 outside the plate 40 for securing the hand lever 37 in the desired position.

The operation is as follows:

As the engine speeds up the governor weights 17 move outward drawing lever 26 downward against the action of spring 32 through parts 23 and 24 to rotate the eccentric fuel control shaft 15 suitably and raise the outer end of the by-pass lever 14 whereby the movement of the plunger tappet 8 causes the suction valve 3 to be opened earlier in the pump plunger stroke, securing the desired decrease in the fuel supply to the engine. In this operation the shoulder 35 of hub 27 moves away from the pin 36 carried by hand lever 37. A decrease in the engine speed results in an inward movement of the governor weights 17 which

allows the spring 32 to move the fuel control shaft 15 in the opposite direction, thus lowering the outer end of the by-pass lever 14 producing a later opening of suction valve 3 for by-passing and thus increasing the supply of fuel to the engine cylinders. In this movement the quantity of fuel supplied is dependent not only on the governor but also on the position of the pin 36 and the engagement therewith of shoulder 35 carried by hub 27. Through handle 38 and hand lever 37 the pin 36 may be set at any position within the limits of the arcuately slotted plate 40 to determine the maximum quantity of fuel which may be delivered by the fuel pumps, the governor operating to control the fuel delivery for quantities less than the adjustable fixed maximum, but inoperable to increase the fuel feed above this maximum quantity as determined by the engagement of shoulder 35 with the pin 36.

A further advantage of this construction resides in the fact that it may readily be attached to any engine control box.

It will readily be understood that the invention is not to be limited to the specific form shown, as many modifications thereof may be made within the invention as defined by the claims.

What is claimed is:

1. A fuel feeding device for internal combustion engines comprising a fuel pump, a fuel by-pass valve, means for operating the fuel by-pass valve including a fuel control shaft determining the point and duration of the opening of said fuel by-pass valve, a governor connected to the fuel control shaft, and an adjustable stop coacting with the fuel control shaft to provide an adjustably fixed maximum fuel limit to the fuel increasing movement of the fuel control shaft.

2. A fuel feeding device for internal combustion engines comprising a fuel pump, a fuel by-pass valve, means for operating the fuel by-pass valve including a fuel control shaft determining the point and duration of the opening of said fuel by-pass valve, a governor connected to the fuel control shaft, a hand lever mounted on the fuel control shaft and free to rotate thereon, a shoulder on the fuel control shaft, a pin carried by the hand lever and coacting with said shoulder to provide an adjustably fixed maximum fuel limit to the fuel increasing movement of the fuel control shaft, and means for securing the hand lever in adjusted position.

3. A fuel feeding device for internal combustion engines comprising a fuel pump, a fuel by-pass valve, means for operating the fuel by-pass valve including an eccentric fuel control shaft determining the point and duration of the opening of said fuel by-pass valve, a governor connected to the eccentric

fuel control shaft, a hand lever mounted on the eccentric fuel control shaft and free to rotate thereon, a peripheral recess in the eccentric fuel control shaft providing a shoulder thereon, a pin carried by the hand lever and coacting with said shoulder to limit to the fuel increasing movement of the eccentric fuel control shaft, and means for securing the hand lever in adjusted position. ¹⁰ In testimony whereof, I have hereunto set my hand.

PHILLIPS P. BOURNE.
